FIG.2.

Louis Gottlieb INVENTOR.
BY W. Hechelman ATTORNEY,

UNITED STATES PATENT OFFICE

133,798

DESIGN FOR A BELT

Louis Gottlieb, Brooklyn, N. Y., assignor to Lidz Bros. Inc., New York, N. Y., a corporation of New York

Application May 15, 1942, Serial No. 106,910

Term of patent 3½ years

To all whom it may concern:

Be it known that I, Louis Gottlieb, a citizen of the United States, residing in Brooklyn, county of Kings, State of New York, have invented a new, original, and ornamental Design for a Belt, of which the following is a specification, reference being had to the accompanying drawing forming part thereof.

The design unit is contained between the buckle and the broken line, as shown in Figure 1, which unit is repeated in regular succession on the belt.

I claim:

The ornamental design for a belt, as shown and described.

LOUIS GOTTLIEB.
